UNITED STATES PATENT OFFICE

NICHOLAS S. VEDDER AND FRANCIS RITCHIE, OF TROY, NEW YORK,
ASSIGNORS TO NICHOLAS S. VEDDER, OF SAME PLACE.

DESIGN FOR PARLOR COOKING-STOVES.

Specification forming part of Design No. 8,012, dated January 19, 1875; application filed December 30, 1874.
[Term of Patent 3½ years.]

CASE A.

To all whom it may concern:

Be it known that we, NICHOLAS S. VEDDER and FRANCIS RITCHIE, each of the city of Troy, in the county of Rensselaer and State of New York, have jointly invented and produced a new and original ornamental Design for Parlor Cooking-Stoves, of which the following is a specification, reference being had to the accompanying cut, print, or engraving of a stove having our said new design.

One part of this invention consists of the design for the cover A, composed of the flat top part b, ornamented convex part c, with lunate openings therein, flat part d, concave molding e, and convex or inclined ornamented portion f, having quadrangular openings therein, and with an outer border-molding, g, all shaped and arranged together so as to present substantially the same appearance as is represented in the aforesaid cut.

Another part consists of the design for the upper end door K, composed of the border ornamentation H, the smooth inclined quadrangular surface l, and the middle compound ornament M, having a diamond-like center and radial transversely ribbed or grooved angular sectors, with lobes or projections at their outer ends, all shaped and arranged so as to appear substantially as shown in the aforesaid engraving.

Another part consists of the design for the oven-door N, composed of the border ornamentation H, the inclined quadrilateral surface o, with rounded uppercorners, and the compound panel ornament P, having a diamond-like center, flanked by oval projections, and radial ribbed sections q, with convex ends and round knobs thereon, alternating with angular sections r, having three-lobed projections at their outer angles, all shaped and arranged as shown in the aforesaid cut.

Another part consists of the design for the upper front door S, composed of the inclined surface t, having a row of rectangular bordered openings therein, and the upper side longer than and parallel to the lower side, and curved ends, and the surrounding border ornamentation u, consisting of a series of sepa-

rate diamond-shaped projections on a narrow raised bed, and curved segment v outside of the end of the said ornamental border u, and all shaped and arranged together so as to appear as represented in the aforesaid engraving.

Another part consists of the design for the illuminating front door W, composed of the border ornamentation H along the top and ends of the oblong rectangular frame, the diamond-shaped ornaments xx on the stiles between the mica-light apertures and the flat arches z, with horizontal ends over said apertures, all shaped and arranged as shown in the aforesaid cut.

Another part consists of the design for the front plate B, composed of the row of oval ornaments a on each end part of the upper section, the branched ornaments h in the corners of the lower section, and the curved surfaces k and m, and tablet n, with border-molding p, scalloped along the inner edge, all shaped and arranged together so as to appear substantially as represented in the aforesaid engraving.

Another part consists of the design for the leg C, composed of the compound central ornament S, tapered downward, and terminated in a knob on the rounded lower end, and grooved longitudinally, and having thereon a rosette at the top, a diamond-like projection in the middle, and an oval projection at the lower part, the plain convex surface surrounded by the scalloped border w and the outer edge-moldings w', all shaped and combined so as to appear substantially as represented in the aforesaid cut.

We do not herein claim the design for the vase on the stove in the accompanying cut or print.

What we claim as our joint invention is—

1. The design for the cover A, composed of the parts b, c, and d, molding e, portion f, and molding g, all shaped, ornamented, and arranged together as herein described.

2. The design for the border H, composed of the series of the diamond-shaped ornaments i, with stocks j, arranged transversely to the

length of the border and pointed inward, as shown and described.

3. The design for the oven-door N, composed of the ornamental border H, inclined surface o, and compound central ornament P, all shaped, ornamented, and arranged together as shown and described.

4. The design for the upper front door S, composed of the inclined surface t, with rectangular openings and curved ends, the ornamental border u, and the curved end v, all shaped and combined as specified and shown.

5. The design for the lower front door W, composed of the border ornamentation H along the top and ends, the diamond-shaped ornaments x on the middle stiles, and the flat arches z, with horizontal ends, over the mica-light openings, all formed and disposed as shown and specified.

6. The design for the front plate B, com-

posed of the rows of lateral ornaments a on the upper section, the corner ornaments h on the lower section, and the intervening curved parts k and m, and tablet n, with border p, all shaped and disposed as described and shown.

7. The design for the leg C, composed of the compound central ornament S, plain convex surface surrounded by the scalloped border w, and the outer edge-moldings w', all shaped and combined as hereinbefore specified, and shown in the accompanying representation.

In testimony whereof we hereunto subscribe our names this 24th day of December, 1874.

NICHOLAS S. VEDDER.
FRANCIS RITCHIE.
